An ornate seal or stamp is positioned at the top left of the page. It features a central figure, possibly a profile of a person, surrounded by decorative scrollwork. Above this figure, the word "Inventor" is written in a cursive, flowing script. Below the seal, the title "Albert A. Radtke" is written in a similar cursive style. Underneath the name, the text "by Arbab Marvin" is written, followed by "atty." at the bottom right.

UNITED STATES PATENT OFFICE.

ALBERT A. RADTKE, OF CHICAGO, ILLINOIS, ASSIGNOR TO ELECTRIC TIME RECORDER COMPANY, OF CHICAGO, ILLINOIS, A CORPORATION OF ILLINOIS.

TIME SYSTEM.

1,184,658.

Specification of Letters Patent. Patented May 23, 1916.

Application filed April 9, 1910. Serial No. 554,322.

To all whom it may concern:

Be it known that I, ALBERT A. RADTKE, a citizen of the United States, residing at Chicago, county of Cook, State of Illinois, have invented certain new and useful Improvements in Time Systems, of which the following is a specification.

The main objects of the present invention are to provide a system wherein an electrically operated time-measuring device is utilized to control a plurality of secondary devices located at a distance; to provide electrically driven means for delivering current impulses to a distribution circuit at intervals recurring with accurate regularity; to provide a time system which is automatic in action, and derives its motive power from a source of electrical energy; to provide a time device having an electrically driven switch-mechanism and time-measuring means operatively connected to govern the movements of the switch mechanism; to provide automatic means for winding the spring of the time-measuring device; and to provide other details of construction and special arrangements of parts whereby reliability and efficiency are insured.

A specific construction embodying this invention is illustrated in the accompanying drawings, wherein—

Figure 1 is a side elevation of the main or master instrument from which the current impulses are sent out. Fig. 2 is a sectional plan of the same on the lines A—A of Fig. 1. Fig. 3 is a diagram of connections. Fig. 4 is an enlarged detail of the control mechanism used to govern the movements of certain of the elements shown in Fig. 1. Fig. 5 is a view of the master instrument as seen from below. Fig. 6 is a sectional elevation through the main shaft of the master instrument.

In the construction shown, the apparatus is provided with a supporting plate 1, adapted for attachment to a wall. This plate may be circular in outline, and may have a screw-threaded periphery for the more ready attachment of a protective cover or dome, not shown.

Projecting from the side of base 1 is a shelf 2 of magnetizable material, such as soft iron, preferably laminated and having apertures within which a plurality of magnetizing coils are seated. This iron shelf serves

as a magnetic field for the coils, and also

serves as a support for a pair of vertical standards 3 and 4, and an octagonal standard 5. These standards carry at their top a horizontal platform 6, on which is mounted a clock escapement 7, which need not here be described in detail. This escapement is operatively connected with a pinion 8 suspended below platform 6 by a suitable bracket. The pinion meshes with a gear 9, which carries on its under surface a spring box 10, within which is a helical clock spring 10', having one of its ends connected to the box, and its other end connected to a bushing mounted rigidly on a shaft 11. This shaft is the main vertical shaft of the apparatus. Except for the connection of the spring to the shaft, the gear 9 and spring box 10 are free to turn about the shaft. A pin 12 projects down from the spring box for engagement with other parts of the mechanism.

The escapement and its coöperating gears and clock spring above referred to, may be regarded as constituting a time-measuring device, effective to regulate the speed with which the device performs its work. The main shaft may be regarded as the winding means for the clock spring.

The driving means whereby the main shaft 11 can be rotated to keep the spring of the time-measuring device always under tension is here shown as electrically operated. It comprises an electro-motive device having three coils or windings 13, 14 and 15, seated in apertures in the laminated iron shelf 2, and having cylindrical armatures 16, 17 and 18, each movable in its respective coil, and each provided with a link which is connected to a common crank pin 19, carried on the lower side of a disk 20. This disk is rigidly secured to the lower end of the vertical shaft 11, and constitutes the conical member of a ball-bearing used to hold the shaft in position. Each of the windings has one of its ends connected to a metal ring 21, serving as a cross connection or junction joint for the coils. Mounted above the windings of this electro-motive device is a switch mechanism comprising a laminated bridge 22, mounted to rotate with the main shaft, and constituting a switch or cross connection for certain other parts of the switch mechanism. The laminations of the switch are riveted to a boss 23, carried on the side of a brass collar 24, which envelops the main

shaft and turns therewith, but is insulated therefrom by a lava bushing 25. The point of attachment to boss 23 is at the approximate middle of the laminated switch, so that the outer ends of the laminations press downward with equal force on the parts on which they bear.

Cooperatively related with the rotary switch is a dial consisting of a horizontal plate 26, of insulating material, carrying on its face a slip ring 27, and three metal segments, 28, 29 and 30. One end of the rotary switch makes contact with the slip ring and its other end makes contact successively with the segments. The contacting ends of the switch are broad enough to bridge the short gap between adjacent segments, so that the circuit through the switch will not be interrupted when the switch moves from one segment to the next.

The segments 28, 29 and 30 are connected respectively to the adjacent ends of the windings 13, 14 and 15. The slip ring 27 is provided with a current supply wire 31, which leads out through the side of the insulated plate 26 and through a tubular passage, and then down through the hollow interior of the hexagonal standard 5 to a suitable insulator 32, through which it may pass out for connection to a source of electrical energy. Current coming from this source through conductor 31 to ring 27 can pass through the switch 22 to one of the segments, say segment 28, and thence through winding 13 to the connecting ring 21, and from that ring back to the source by way of a conductor 33. The magnetism thereby set up by winding 13 tends to draw the armature 16 inward and so tends to rotate the main shaft and shift the switch or bridge 22 to an adjacent segment. In a certain sense, the coils and the switch mechanism may be regarded as a motor adapted to take current through its three coils in succession, and adapted to shift connections to the coils in such a way that continuous rotation will result. The switch mechanism has however a function other than that of shifting current from one coil to another, and in order that it may fulfil this additional function, the segments 28, 29 and 30 are provided respectively with conductors 34, 35 and 36, which lead down through the insulating disk 26 and through the iron field frame 2, and then out from the instrument, together with conductor 33, to serve as distributing conductors for the other instruments, which are to be connected thereto, and receive current therefrom. Each time the rotary switch 22 shifts connections from one coil of the electro-motive device to another; it also shifts connections from one distributing conductor to another; thereby interrupting the flow of current in one, and establishing the flow in the next. It will

be seen that if these periodic changes in current in the distributing conductors can be made to follow each other at regular and predetermined intervals, any number of time-indicating instruments, or the like, connected across the conductors, can be actuated in synchronism.

The control mechanism whereby the movements of the electro-motive device and the switch mechanism are made dependent on the time-measuring device, comprises a cam 37 mounted to rotate freely on the main shaft and having a short slot 38 for the reception of the pin 12 which projects down from the spring box of the time-measuring device. This pin moves at constant speed, and therefore steadily rotates the cam about the main shaft 11. The cam may have three arms, as shown in Fig. 4, and may rotate counter-clockwise. The control mechanism also includes a tripping member 39, having projecting horns 40 and 41, which embrace opposite sides of the cam 37, and carry small rollers for engagement with the periphery of the cam. At the opposite end, this tripping member is pivotally mounted at 42, and carries a pallet 43, having convergent faces 44 and 45. The control mechanism also includes a holding member 46, having at one end a pair of convergent arms with contact points 47 and 48, arranged to strike respectively against the pallet faces 44 and 45, and to slip therefrom when the pallet swings about pivot 42. This holding member 46 is pivotally mounted near its center, and has an opening with irregular edges forming two shoulders 49 and 50. Immediately below this opening is a 6-tooth pinion 51, having three pins which project upward into the opening of the holding member in such position that they can strike in succession against the shoulders 49 and 50. Meshing with the pinion 51 and urged forward by the electromotive device is a 6-tooth gear 52, having its teeth arranged in pairs, and having rigid connection with the main or driving shaft 11. This control mechanism interposed between the time-measuring device and the electromotive device may be regarded as a holding means for preventing movement of the electro-motive device, and its switch, except at such time intervals as may be prescribed by the time-measuring device.

The system wherein the above described apparatus may be used is indicated diagrammatically in Fig. 3 where A represents a rotary switch mechanism, B a source of electrical energy, and C and D, secondary units such as clocks, time stamps or the like, connected across the distributing conductors of the system. Each of these secondary units may be of the general type described in United States Patent No. 921,280, issued to me May 11, 1909, and may com-

prise a rotary armature 53 having polar extensions in operative relation to a plurality of magnetizing coils 54, each connected to a distributing conductor and all arranged in such a way that when the coils are magnetized in succession, the rotary armature will turn. By suitably timing the supply of current to the respective coils, the time of rotation of the armature can be accurately governed, and the secondary unit may be made to follow the movements of the switch mechanism at A. If the switch mechanism shifts segments once each minute, the secondary units will also move once each minute, and can be regarded as synchronized with the master time-measuring instrument once each minute.

The source of current B may be a storage battery or a dynamo electric machine, either direct or alternating current. It delivers current through conductor 31 to slip ring 27, as heretofore recited, and its other terminal is connected through conductor 33, to the ring 21, forming the cross connection for the three coils of the electro-motive device. That same terminal of the source is also connected to a common return conductor 55 leading from all the secondary units which are connected to the distributing conductors.

The operation of the system is as follows: The escapement 7 allows pinion 8 and gear 9 to rotate at constant speed under the driving impulse of the energy initially stored in the clock spring carried in spring box 10. The pin 12, depending from the spring box, moves at constant speed, and turns the cam 37 on its supporting shaft. When the cam reaches such position that the roller-tipped horn 41 can move from the periphery of the cam toward the shaft, it does so, and the tripping member 39 swings slightly on its pivot 42, and shifts the pallet surface 44 sufficiently to allow the point 47 to slip off the edge of the surface, thus giving the holding member 46 a slight swinging movement about its central pivot. This movement is enough to disengage the shoulder 49 from its contacting pin allowing the pinion 51 to rotate a distance corresponding to one tooth, or until the next pin strikes against the shoulder 50. When the pin does so strike on the shoulder 50, it swings the holding member 46 back beyond its initial position until the hooked end 48 comes in contact with the pallet face 45. Its pressure on that face swings the tripping member 39 back until its roller 40 bears on the periphery of cam 37. The movement of pinion 51 above described serves to release the 6-tooth gear 52. As previously stated, this gear is mounted rigidly on the main shaft, and serves to prevent free rotation of the shaft under the continuously operative torque of

the three actuating coils. But when the 6-tooth gear 52 is released by pinion 51, the scarcity of teeth on its periphery allows it to move a considerable distance, giving the main shaft a quick, partial turn, and moving the switch member 22. This shifts connections, not only to the coils of the electromotive device, but also to the distributing conductors. After this swing of the switch member, the main shaft remains stationary until the time-measuring device has turned the cam 37 into position to release the horn 40 of the tripping member 39, and thereupon the control mechanism again allows the 6-tooth gear 52 to rotate, but this time the rotation is but slight corresponding to the angular width of the short distance between two adjacent teeth.

The operation above recited repeats itself over and over, the main shaft making a long swing and then a short swing, in regular succession, and at each long swing, shifting the connections to the electro-motive device and simultaneously shifting the connections to the distribution circuit. Every swing of the shaft winds the spring of the time-measuring device. By so proportioning the escapement and the gears of the time-measuring device, the long swings of the shaft may come once a minute, thereby producing current impulses in the distribution circuit, which also come once a minute, and which produce movement in the secondary units once a minute. Whether these secondary units be clocks or time-stamps, or whether they be something quite different in function, but still requiring actuation at definite and predetermined time intervals, they can be regulated all together by the means above described, and all will take their speed of motion from the main or master time-measuring device.

In the claims I have used the words "lost motion mechanism" to include those elements for instance associated with the element 39.

In a certain sense, the apparatus of Fig. 1 may be regarded as a self-winding master clock, electrically operated, and capable of maintaining a plurality of secondary clocks in synchronism with one another, and substantially in synchronism with itself.

What I claim as new, and desire to secure by Letters Patent of the United States, is:

1. The combination of a rotary electro-motive device, a rotary switch mechanism continuously transmitting current thereto, connections between said switch mechanism and said electro-motive device to insure rotation of said switch by said electro-motive device each time said electro-motive device rotates, a time-measuring device, and a control mechanism operatively connected between said time-measuring device and

- said switch mechanism to permit rotary movement of said switch mechanism at predetermined time intervals.
2. The combination with a source of current of a switch mechanism continuously in circuit therewith, a motive device receiving current through said switch mechanism, and continuously tending to move said switch mechanism, a spring-driven time measuring device, a mechanical connection between said switch mechanism and said time measuring device, and means for delivering power to said time measuring device each time said switch mechanism moves.
3. The combination of a source of electrical energy, distributing conductors, time measuring devices energized thereby, rotary switch mechanism adapted to deliver energy from said source to said conductors in succession, a main time-measuring device, and means energized by current from said source and mechanically connected to move said switch and to deliver power to said time-measuring device intermittently.
4. The combination of an electro-motive device having a driving shaft, a source of current for said device, a rotary switch mounted to turn with said shaft, control mechanism connected to govern movement of said shaft, and a time-measuring device connected to actuate said control mechanism, and having a spring connected to said shaft and periodically wound by movement thereof.
5. The combination of a plurality of coils, a plurality of armatures, one for each of said coils, a shaft, pivoted links connecting said armatures to drive said shaft, a rotary switch mounted on said shaft, time-controlled means for intermittently delivering current to said coils in succession by way of said switch and a driving connection between said shaft and said time-controlled means.
6. The combination of a plurality of coils, armatures for said coils, a rotary shaft, means for connecting said armatures to rotate said shaft, a rotary switch carried by said shaft, means for delivering current to said coils through said switch, and means for limiting free rotation of said switch at predetermined time intervals.
7. The combination of a plurality of windings, armatures for said windings, a shaft operatively connected for rotation by said armatures, switch mechanism actuated by said shaft, means for delivering current to said windings through said switch mechanism, distributing conductors successively connected in circuit with said switch mechanism, and mechanical means for holding said switch mechanism at predetermined time intervals.
8. The combination of switch mechanism, a shaft for moving said switch mechanism,
- means continuously operative for inducing movement of said shaft, a time-measuring device, a cam operatively connected to said time-measuring device and moved thereby, a tripping member actuated by said cam, a holding member in position to be released by said tripping member, a pinion periodically held by said holding member, and a gear meshing with said pinion and operatively connected to said shaft to permit movement thereof when said tripping member releases said holding member.
9. The combination of a shaft, means normally tending to rotate said shaft, a cam mounted to turn about said shaft, a time-measuring device having a winding spring operatively connected to said shaft, said time-measuring device being operatively connected to rotate said cam at predetermined speed, a tripping member having horns at either side of said cam, and having a pallet with convergent faces, a holding member having arms adapted to swing into contact with said faces, a pinion having pins adapted to move into contact successively with shoulders on said holding member, and a gear meshing with said pinion and mounted on said shaft, said gear having its teeth spaced irregularly.
10. The combination of an escapement, a gear operatively connected therewith, a winding spring carried by said gear, a winding shaft connected to one end of said spring, a cam mounted to rotate on said shaft and having operative connection with said gear, tripping means actuated by said cam, holding means released by said tripping means, a gear on said shaft and operatively connected with said holding means, a switch on said shaft, and an electro-motive device having windings which receive current in succession through said switch, said electro-motive device having means for turning said shaft.
11. The combination of a plurality of coils seated in a magnetizable frame, armatures for said coils, a rotary shaft, links operatively connecting said armatures to said shaft, a switch movable with said shaft, means for conducting current to said coils in succession by way of said switch, a gear mounted on said shaft, a time-measuring device having a spring connected at one end to said shaft, a cam normally moved by said time-measuring device, a tripping member actuated by said cam, a holding member in position to be released by said tripping member, and a pinion engaging with said gear and periodically released by said holding member.
12. The combination of distributing conductors, a source of electrical energy, switching means for delivering current from said source to said distributing conductors in succession, a motive device energized by

- current from said source by way of said switching means, and continuously tending to move said switching means, and means for automatically releasing said switching means at predetermined time intervals. 5 said lost motion mechanism, and means whereby said switch controls the energization of said electromagnetic means, said electromagnetic means including a plurality of coils adapted for energization in rotation.
13. The combination with a plurality of coils, a rotary shaft, movable means controlled by said coils to rotate said shaft, a switch carried by said shaft, means whereby 10 said switch controls the supply of current to said coils, means for holding said shaft normally against rotation, and an escapement mechanism to periodically release said means. 14. A master mechanism of the character described having a switch adapted for periodic movement, a shaft carrying said switch, electromagnetic means for actuating said shaft, a lost motion control mechanism 15 interposed between said shaft and said switch, and an escapement mechanism to control said lost motion mechanism. 15. A master mechanism of the character described having a switch adapted for periodic movement, a shaft carrying said switch, electromagnetic means for actuating said shaft, a lost motion control mechanism 20 interposed between said shaft and said switch, and an escapement mechanism to control said lost motion mechanism, and means whereby said switch controls the energization of said electromagnetic means. 16. A master mechanism of the character described having a switch adapted for periodic movement, a shaft carrying said switch, electromagnetic means for actuating said shaft, a lost motion control mechanism 25 interposed between said shaft and said switch, an escapement mechanism to control said lost motion mechanism, and means whereby said switch controls the energization of said electromagnetic means. 30
17. A master mechanism of the character described having a switch adapted for periodic movement, a shaft carrying said switch, electromagnetic means for actuating said shaft, a lost motion control mechanism 35 interposed between said shaft and said switch, and time controlled mechanism to control said lost motion mechanism. 18. In a device of the character described the combination with a watch spring, electromagnetic means for periodically winding said watch spring, a contact making device to control the operation of said electromagnetic means, and controlling mechanism under the control of said spring to control said contact making device, said means including a Geneva wheel mechanism. 19. In a device of the character described the combination with a watch spring, electromagnetic means for periodically winding said watch spring, a contact making device to control the operation of said electromagnetic means and driven by said electromagnetic means, and controlling mechanism under the control of said spring to control said contact making device. 70

In witness whereof, I have hereunto set my hand this second day of April, A. D. 1910.

ALBERT A. RADTKE.
